5 Claims. (Cl. 51—105)

This invention relates to a special grinding machine, so arranged as to automatically grind casting fins and the finishing allowance on the periphery of a brake drum, being characterized by feeding brake drums at predetermined intervals by feeding arms, rotating the drum after it is held in a central position to grind the fins of the drum periphery, followed by removal of the drum from this position after grinding and mechanically transferring the drum by another lever to the next processing step.

The invention will be understood better by the following description with reference to the accompanying drawings illustrating an embodiment of this invention in which:

FIG. 1 is a front view showing in section the main elements;

FIG. 2 is a side elevational view;

FIG. 3 is an enlarged fragmentary front view showing a section of the feeding arm and sliding member; and

FIG. 4 is an enlarged fragmentary front view showing a section of drum fitting portion.

In FIG. 1, on the charging side, a roller conveyor 1 is slightly slanted or inclined at one end so as to slide a brake drum D thereon. The conveyor thereafter is substantially horizontal. Sliding members 3, 3 are provided with feeding arms 2, 2 to push the brake drum D from behind and on both sides thereof. Members 3 are slidably connected to horizontal spaced guide shafts 5, 5, mounted on frame 4. Sliding members 3, 3 are pivotally connected to feeding levers 7, 7 through pins 9 and complementary elongated holes 8 disposed in the upper end of levers 7. The lower ends of levers 7 are mounted on a transverse shaft 6 in turn mounted on frame 4. Feeding levers 7, 7 are disposed to swing around transverse shaft 6, by virtue of an oil pressure cylinder 10 fixed on frame 4 together with said levers. Feeding arms 2, 2 are pivotally swingable in a vertical direction to sliding members 3 by pins 11 connected thereto as shown in FIG. 3. The sliding members 3 are provided with supporting pins 13 urged upwardly by a compression coil spring 12. The supporting pins 13 always keep feeding arms 2 at such height as to push the brake drum D on the roller conveyor 1 toward the center portion of machine. On the right side of roller conveyor 1, at the height less than that of conveyor 1, is the neck of a brake drum mounting device 14. Device 14 is rotatably and vertically inserted by a bearing into frame 4. On the upper portion of the drum mounting device, as shown in FIG. 4, are drum clamping claws 15 in the form of bell cranks. Claws 15 project upwardly from three sides of device 14 and are spaced equal distances therearound and equal distances from the periphery of the drum mounting device so as to determine the center of drum D. Each drum clamping claw, is swingably fixed thereabout by a pin 16 in the middle thereof. Each end of clamping claws 15, 15, 15 is held from upward movement by push pins 17 projecting downwardly into the drum mounting device 14 and is held from downward movement by compression coil springs 18. However when pin 17 is pushed downwardly with a force overcoming the force in spring 18 the upper

2

end of clamping claw 15 is moved inwardly, as shown by the double dotted chain line 15' in FIG. 4, to secure the drum D on the loading plate 25 at the center of drum. The clamping claws 15 are normally disposed outwardly of plate 25 by springs 18, as shown in FIG. 4. To the lower end of the brake drum mounting device 14 is secured a spiral gear 19 in engagement with a spiral pinion 20. The spiral pinion 20 is connected to a multiple disc clutch 21 provided on the side frame and operative to rotate drum mounting device 14 at predetermined intervals of time. Multiple disc clutch 21 is actuated by the movement of a clutch lever 22 connected to a rod 24, which rod in turn is actuated by an oil pressure cylinder 23, horizontally disposed on frame 4, as shown in FIG. 2. A lifting rod 26 is rotatable with drum loading plate 25. Plate 25 has a plurality of holes therein disposed below the push pins 17 which can extend therein. The lower part of rod 26 is actuated by an oil pressure cylinder 27 fixed on frame 4, so as to raise loading plate 25 to the position indicated at 25' in FIG. 1 adjacent roller conveyor 1 if desired, and to lower it onto the drum mounting device 14 as shown in FIG. 2.

On the upper part of drum mounting device 14 is a drum holder 29, having a drum holding plate 28 which 25 rotates on the same vertical axis as lift rod 26. Holder 29 is moved vertically by means of the oil pressure cylinder 30 disposed on frame 4. The push rods 17 depend from plate 28. On the right side of drum mounting device 14, and adjacent the end of a sloped roller conveyor 31 is a sliding member 33, with a claw for removing brake drum D from loading plate 25. Sliding member 33 is mounted on guide shaft 34 and connected to a lever 36, swingable about a transverse shaft 35 mounted on frame 4. A sliding piece or member 38 is journaled 30 on sliding member 33 and extends into an elongated opening 37 at the upper end of lever 36. Lever 36 is connected with feeding lever 7 by a rod 39 operated by oil pressure cylinder 10 in association with feeding levers 7.

In the operation of the present invention, a brake drum fed on roller conveyor 1 is pushed by the spaced feeding arms 2 under the action of oil pressure cylinder 10 of feeding levers 7 and transferred onto drum loading plate in the position indicated at 25'. As soon as brake drum D is loaded on the drum loading plate 25 on drum mounting device 14, drum holder 29 on the upper part of mounting device is moved downwardly by oil pressure cylinder 30. At the same time lifting rod 26 is lowered into the interior of its oil pressure cylinder to lower loading plate 25 with drum D onto drum mounting device 14.

At this time push pins 17, 17, 17 project through the holes in plate 25 and actuate clamping claws 15, 15, 15 inwardly and fix brake drum D thereon.

At this time oil pressure cylinder 10 is actuated to swing feed levers 7 to the left to return feeding arms 2, 2 to their original positions passing under the next drum D without interfering with the descent of brake drum D, while lever 36 on the discharging side of conveyor 1 swings to the left by means of rod 39 to move claws 32 above the drum mounting device 14.

Clutch lever 22 of multiple disc clutch 21 is then operated by oil pressure cylinder 23 and transmits through pinion 20 the motion of motor M to gear 19 to rotate the spiral gear 19 to grind the periphery of brake drum D on drum mounting device 14 with a high speed grinding wheel G, as shown in FIG. 2.

The grinding wheel G is then moved away from brake drum D. Lever 22 of multiple disc clutch 21 is then operated in reverse by oil pressure cylinder 23. When drum mounting device 14 stops rotating, drum holder 29 is raised by oil pressure cylinder 30 and at the same time clamping claws 15 are expanded outward by compres-

sion coil springs 18 to release the clamped brake drum D. Then, when loading plate 25 is raised to position 25', claw 32 moves brake drum D onto roller conveyor 31 while lever 36 swings to the right under the action of oil pressure cylinder 10. At this time feed levers 7 linked with lever 36 swing to the right to feed the next brake drum D onto loading plate 25 by means of feeding arms 2 and the cycle is repeated.

Drum D, transferred to roller conveyor 31 is then automatically transferred to the next process step.

Though at present due to striking development of casting technique, a number of parts of machine and automobile are made of casting, to finish them completely, grinding operation such as removal of fin and flaw as well as rough grinding of finishing allowance as the first step plays an important roll prior to finishing the goods. Since the removal of casting fin has hitherto been performed manually with a chisel, hand grinder and the like, the operator is likely to become tired. The operation itself is also dangerous.

The present invention is intended to provide a simplified grinding process both in time and labor.

I claim:

1. A grinding machine for a brake drum comprising a frame, a horizontal brake drum loading plate for holding a brake drum thereon while its circumferential periphery is being ground, a first conveyor adjacent one side of said plate for feeding a brake drum onto said plate, feed arm means for pushing a brake drum from said conveyor onto said plate, clamping means for engaging the outer periphery of said drum to fix it on said plate during the grinding operation, means for rotating said plate and drum about a vertical axis during the grinding operation, a second conveyor adjacent the other side of said plate for receiving a ground drum therefrom, and claw means extending into the center of said drum for pulling said ground drum from said plate onto said second conveyor.

2. The machine of claim 1, wherein said feed arm means comprise spaced arms pivotally connected on

sliding members, spring means biasing said arms in an upward direction and feeding levers for reciprocating said sliding members in a horizontal direction.

3. The machine of claim 1, wherein said claw means comprise a claw sliding member with a claw thereon, a lever pivotally swingable in a vertical direction and having its upper end connected to said claw sliding member.

4. The machine of claim 3, wherein said plate is rotated by a clutch member operatively connected to a pinion and gear member secured to said plate for rotation therewith.

5. A grinding machine for a brake drum comprising a frame, a horizontal brake drum loading plate for holding a brake drum thereon while its circumferential periphery is being ground, a first conveyor adjacent one side of said plate for feeding a brake drum onto said plate, feed arm means for pushing a brake drum from said conveyor onto said plate, clamping means for engaging the outer periphery of a drum to fix it on said plate during the grinding operation, said clamping means including a plurality of circumferentially spaced clamping claws consisting of bell crank levers, actuating means disposed above said crank levers operatively connected to said levers to move vertically downwardly to cause said claws to grip the outer periphery of a drum disposed on said plate, means for rotating said plate and drum about a vertical axis during the grinding operation, a second conveyor adjacent the other side of said plate for receiving a ground drum therefrom and claw means extending into the center of said drum for pulling said ground drum from said plate onto said second conveyor.
